COMBINED GUARD AND HOLDING STRIP FOR A CARPET

William W. Smith, 730 S. Garfield,
Denver, Colo. 80209

Filed June 20, 1966, Ser. No. 2,733

Term of patent 14 years

(Cl. D92—4)

FIG. 1 is a top plan view of a combined guard and holding strip for a carpet showing my new design;

FIG. 2 is a top plan view thereof in a reversed position, the broken line showing of a carpet being for purposes of illustration only;

FIG. 3 is an elevational view taken in the direction of 3—3 of FIG. 1;

FIG. 4 is a side elevational view of my new design;

FIG. 5 is a bottom plan view thereof; and

FIG. 6 is a cross sectional view taken on the lines 6—6 of FIG. 1.

I claim:

The ornamental design for the combined guard and holding strip for a carpet, as shown and described.
